(57) **CLAIM**

The ornamental design for a generator parallel connector, as shown and described.

DESCRIPTION

FIG. 1 is a top-front-right perspective view of a generator parallel connector;

FIG. 2 is a bottom-front-right perspective view thereof;

FIG. 3 is a top-rear-left perspective view thereof;

FIG. 4 is a front elevation view thereof;

FIG. 5 is a rear elevation view thereof;

FIG. 6 is a right elevation view thereof;

FIG. 7 is a left elevation view thereof;

FIG. 8 is a top plan view thereof; and,

FIG. 9 is a bottom plan view thereof.

The broken lines are included for the purpose of illustrating portions of the generator parallel connector that form no part of the claimed design.
